Inventor:

Frans Eugen Férier

UNITED STATES PATENT OFFICE.

FRANÇOIS EUGENE FÉRIER, OF LYON, FRANCE.

DESIGN FOR SILK CLOTH.

• 50,255.

Specification for Design.

Patented Jan. 30, 1917.

Application filed December 20, 1915. Serial No. 67,925. Term of patent 3½ years.

To all whom it may concern:

Be it known that I, FRANÇOIS EUGENE FÉRIER, a citizen of the Republic of France, residing at No. 10 Rue Calliet, in the city of Lyon, Republic of France, have invented a new, original, and ornamental Design for Silk Cloth, of which the following is a specification, reference being had to the accompanying drawing, forming a part thereof.

The figure is a plan view of a piece of silk cloth, showing my new design.

I claim:

The ornamental design for silk cloth, as shown in the drawing.

FRANÇOIS EUGENE FÉRIER.

Witnesses:

VON VERDRE,

JOHN J. ERNSTEN.
